US00D758644S

(12) **United States Design Patent**
Deluca et al.

(10) **Patent No.:** **US D758,644 S**
(45) **Date of Patent:** **** Jun. 7, 2016**

(54) **COMBINED BOTTLE LIGHT AND HELMET SHADE**

(71) Applicant: **AXIS SOURCING GROUP, INC.**,
Concord, CA (US)

(72) Inventors: **Domenico F. Deluca**, Concord, CA
(US); **Mark Knoll**, Concord, CA (US)

(**) Term: **14 Years**

(21) Appl. No.: **29/519,894**

(22) Filed: **Mar. 9, 2015**

(51) LOC (10) Cl. **26-99**

(52) U.S. Cl.

USPC **D26/125**

(57) **CLAIM**

The ornamental design for a combined bottle light and helmet shade, as shown and described.

DESCRIPTION

FIG. 1 is a perspective top view of a combined bottle light and helmet shade showing our new design;
FIG. 2 is a perspective bottom view thereof;
FIG. 3 is a top plan view thereof;
FIG. 4 is a bottom plan view thereof;
FIG. 5 is a front elevation view thereof;
FIG. 6 is a rear elevation view thereof;
FIG. 7 is a right side elevation view thereof; the left side elevation view is the mirror image of FIG. 7;
FIG. 8 is a first perspective top view of the combined bottle light and helmet shade shown in an environment of use;
FIG. 9 is a second perspective top view of the combined bottle light and helmet shade shown in an environment of use;
FIG. 10 is a third perspective top view of the combined bottle light and helmet shade shown in an environment of use; and,
FIG. 11 is a perspective bottom view of the combined bottle light and helmet shade shown in an environment of use.
The broken line portions shown in FIGS. 8-11 illustrate environmental subject matter only and form no part of the claimed design.

1 Claim, 7 Drawing Sheets
